(57) **CLAIM**

The ornamental design for an amplifier case, as shown and described.

DESCRIPTION

FIG. 1 is a top side perspective view of an amplifier case, embodying my new design;

FIG. 2 is a top plan view thereof;

FIG. 3 is a side elevation view thereof;

FIG. 4 is a front elevation view thereof;

FIG. 5 is an opposite side elevation view thereof;

FIG. 6 is a back elevation view thereof; and,

FIG. 7 is a bottom plan view thereof.

The objects shown in broken lines are shown for environmental purposes only and form no part of the claimed design.
